BURNER FOR STOVES.

1,292,643.

Specification of Letters Patent.

Patented Oct. 4, 1921.

Application filed May 1, 1920. Serial No. 378,040.

To all whom it may concern:

Be it known that I, HENRY B. HEMPHILL, a citizen of the United States, residing at Eldorado, in the county of Saline and State 5 of Illinois, have invented certain new and useful Improvements in Burners for Stoves, of which the following is a specification, reference being had to the accompanying drawings.

10 This invention relates to an improved burner for stoves and an object is to provide a device of this kind which is practical, simple and efficient in construction and can be cheaply made and sold at a reasonable 15 profit.

Another object is to provide a burner which is automatic in operation and is capable of giving a great amount of heat with a relatively small supply of fuel, and further 20 to provide a burner particularly adapted and constructed for using oil, preferably a natural crude oil and also to so construct the burner that a relatively small amount of oil or fuel may be contained in 25 the fire pot or cup but which will be sufficient to generate sufficient heat.

Still another object is the provision of a burner including an air chamber to permit a proper amount of air to mix with the 30 vapor from the oil to insure a proper combustion of the fuel for burning purposes.

A further object is the provision of a fuel cup in which the fuel is fed and wherein the fuel is vaporized owing to the heat 35 on the interior of the stove.

A still further object is the provision of a fire pot disposed under the fuel cup including a coil wire fabric or gauze or metallic wool in the bottom thereof and into which 40 fire box the over-flow of the oil from the cup passes, and should there be any over-flow from the fire box it will pass into the air chamber below the box in order to be drawn off.

45 Also the invention aims to provide means for baffling or confining the products of combustion so as to prevent them from passing upwardly and outwardly from the stove.

Furthermore the invention aims to provide 50 a fire pot which is adjustable relatively to the burner cup, and which acts to regulate the supply of air through the air chamber. In other words, by lowering the fire pot on the main air tube, the air rising up-

wardly through the air chamber will be more 55 or less retarded and by raising the fire pot on the main air tube relatively to the air chamber, a greater and freer supply of air is allowed to rise and cause a better combustion of the fuel.

Moreover, it is the aim to provide an asbestos filling surrounding the oil cup, in order to insure a better burning of the fuel, and to avoid an excessive over-flow of the 65 fuel from the cup, for the reason that the asbestos will act as a wick, and will tend to draw the fuel or oil so that it can be burned from the wick.

Also it is the aim to provide means on the valve of the supply pipe to limit the 70 valve in its open position in order to limit the supply of fuel to the cup according to the size of the stove casing and the size of the fire pot and the burner relatively to the size of the room to be heated.

In other words, the valve is capable of being opened a certain distance so that a certain requisite quantity of oil is allowed to enter the cup and no more. The valve can be closed so as to decrease the flow of 80 oil, but the valve is limited so that but a requisite quantity of oil is permitted to enter the cup according to the size of the stove in which the burner is used and the size of the room to be heated.

85 The invention comprises further features and combination of parts, as will be hereinafter set forth, shown in the drawings and claimed.

In the drawings:—

90 Figure 1 is a vertical sectional view through the improved burner, showing the same mounted in a casing and employed mainly as an oil burning stove.

Fig. 2 is a transverse sectional view on 95 line 2—2 of Fig. 1, illustrating the fact that the air chamber has a plurality of air tubes, say for instance, four in number rising upwardly from the bottom of the air chamber.

Fig. 3 is an enlarged detail view of the 100 oil cup, the oil jet and the adjustable jet sleeve, all of which constitute the burner proper.

Fig. 4 is an enlarged detail view of the controlling valve mounted on the supply 105 pipe from the oil tank to the oil burner cup, showing means whereby the valve is limited in its open position so as to permit a maxi-

mum flow of oil to the burner cup, according to the size of the burner and stove and according to the size of the room to be heated.

Fig. 5 is a sectional view on line 5—5 of Fig. 4.

Fig. 6 is a view partly in elevation and partly in section of a coal burning stove, equipped with the improved oil burner, thereby converting the coal burning stove 10 into an oil burning stove.

Fig. 7 is an enlarged detail sectional view through the fire pot, the air chamber, the central air tube 16, and also through the adjustable jet sleeve and oil cup; and

Fig. 8 is a plan view of the construction shown in Fig. 7.

Referring to the drawings, 1 designates a main or stove casing comprising a base 2, the cap plate 3, and arranged to one side of 20 the main or stove casing and connected thereto, as by means of the bracket 4, is an oil or fuel tank 5. A tube or pipe 6 is communicatively connected to the top of the tank 5, and engages through the wall of the 25 main or stove casing 1 and extends upwardly into the flue 4 so as to carry off any gas which may collect between the level of the oil or fuel and the top of the tank. A pipe 7 is connected to the bottom of the tank and is 30 provided with a valve 8 and a trap 9. The trap 9 is provided for the purpose of preventing the flame or heat from traveling back through the pipe or tube into the fuel or oil, which would cause combustion. This 35 tube or pipe 7 passes through the wall of the main or stove casing and is provided with a downwardly turned end 10, which is disposed concentrically over the burner. The tank 5 has a filling opening 11 whereby the 40 fuel may be allowed to enter the tank. Mounted on the side of the tank is a conventional form of gage 12 for the purpose of indicating the level of the oil or fuel in the tank.

The main or stove casing which is constructed preferably in the shape as shown in Fig. 1 as its base 13^a provided with a flanged opening 13^b, the flange 13^c of which extends inwardly. Fitted in the opening 13^b of the 50 base 13^a is an air chamber 14, the wall 13 of which is tapered as shown. Rising upwardly from the bottom of the air chamber 14 is a combined burner and air tube 16. The lower end of this tube 16 is threaded 55 into the bottom of the air chamber 14, there being a shoulder 18 to limit the downward movement of the tube 16. A nut 19^a is threaded on the lower end of the tube 16 in order to hold the tube 16 secure. Also rising from and threaded into the bottom of the air chamber 14, and communicating with the atmosphere under the stove is a plurality 60 of air tubes 15 through which air is allowed to enter the air chamber 14. Adjustably mounted upon the air tube 16 by means of

its threaded connections therewith is a fire pot 17, which has a chamber 17^a. This fire pot 17 is conical or tapered correspondingly to the air chamber 14. Owing to the fire pot being threaded upon the air tube 16 it will be noted that the fire pot is capable of adjustment on the tube relatively to the air chamber 14 and relatively to the burner, so as to regulate the burning of the oil and so as to regulate the air rising from the air 75 chamber 14. Connected to the upper end of the combined oil cup support and air tube 16 by means of threads or the like shown at 16^a is a hollow T 19. This T has a second air chamber 20 and connected to 80 the ends of the T as by means of the unions or caps 21 are elbows 22 which support the outlet air tubes 23 in order to permit the escape of air from the chamber 20 of the T casing.

Elbows 24 are connected to the sides of the T and support outlet air tubes 25. Supported upon the T is a burner cup 26 into which the crude oil or fuel is received and from which the fumes rise and mix with the air escaping from the tubes 23. After the burner is once started, the oil or fuel vaporizes. The down-turned end of the pipe 7 has adjustably connected thereto as at 27 the sleeve 28, the lower portion 29 of 90 which is larger than the extremity of the down-turned end 10 of the pipe or tube 7 so as to permit the fuel to rise therein. The extremity of the down-turned end 10 of the pipe or tube 7 is tapered and terminates in a small opening 28^a so that the fuel or oil is allowed to enter the fuel cup in a relatively small quantity. In other words, the flow of fuel is steady, but the flow is relatively small. Air is allowed to pass upwardly into the air chamber 14 through the base of the casing 1 and together with the air emanating from the up-turned air tubes 23, a proper combustion of the fuel is assured.

In surrounding relation to the adjustable jet sleeve 28 and resting upon the upper marginal edge of the oil cup is an asbestos cord 27^a which acts to absorb the oil from the cup and from which the oil burns as the oil is attracted thereby. But a very small quantity of oil is allowed to enter the oil cup, and it will be noted that the lower marginal edge of the jet sleeve is provided with a plurality of recesses 27^b, which permit the oil to pass from under the sleeve into the oil cup and rise therein, it being obvious that the level of the oil can at no time be considerably higher than the lower outlet end of the jet orifice or opening 28^a and which level will be sufficient to permit it to be absorbed by the asbestos cord. However, should the valve 8 be opened to its fullest extent increasing the flow of oil, the level of the oil will be raised slightly so that the oil will

slightly over-flow the upper marginal portion of the side of the oil cup, and in this case the oil enters the fire pot 17 carrying with it the flame. The oil will circulate 5 and spread through the metallic wool in the fire pot, and will burn off, hence increasing the heat in the stove.

Arranged in the bottom of the fire pot 17 is a filling of coiled wire gauze or fabric, or 10 metallic wool 33. Should there be an over-flow of the fuel from the fire pot into the bottom of the air chamber, the over-flow of the oil or fuel may be drawn off by the drain cock 34, which is carried by the base of the 15 stove. A pan 35 is disposed under the base of the main or stove casing 1 in order to receive the drainage from the air chamber 14. Surrounding the air chamber 14 and within the stove casing is a dead air space 36. 20 A conical baffle or detaining or confining member 38 is arranged above the burner cup, and which is supported by the brackets 37. The lower portion of this baffle or heat contacting member is relatively large, while 25 the upper end thereof terminates in a relatively small opening 39. As the heat rises from the burner it is baffled and eventually passes out through the opening 39 and into the combustion chamber 40, and it finally 30 passes off from the stove to the atmosphere through the pipe or flue 41. A suitable door 42 is carried by the main or stove casing 1 and through which access may be had to the interior of the stove for adjusting or 35 repairing the burner. It is obvious that an operator may open the door and adjust the fire pot 17 upon the tube 16.

In the operation, the oil or fuel from the tank 5 is allowed to flow into the burner 40 cup where it is first ignited, and as the burner heats up, the vaporizing of the oil or other fuel in its crude state is greatly facilitated, and owing to air being allowed to pass 45 through the tube 6, and out through the tubes 23 and allowed to emanate from the tubes 15, proper combustion and vaporizing of the fuel is assured.

By means of the sleeve being submerged 50 in the oil or fuel in the burner cup, there will be no flame adjacent the oil jet also no soot or carbon can collect on the oil jet thereby eliminating any possibility of hindering 55 the flow of oil in the cup. When the oil is turned on and a full blast fire results, the oil in the cup over-flows the cup and into the fire pot 17 carrying with it the flame, and then in such case the level of the oil 60 will be substantially $\frac{1}{4}$ " deep. As the T supports the oil cup over the fire pot 17, air is supplied to the fire pot through the medium of the T and the tir tube 16.

With a burner of this kind there is always a relatively small supply of oil in the burner, say for instance, about $\frac{1}{2}$ pint.

65 Carried by the valve stem of the valve 8 is

a collar 8^a which is held in different adjusted positions by the set screw 8^b. Projecting radially from the collar is an arm 8^c which is designed to contact with the projection 8^d. It will be noted that when the burner is equipped in a casing as shown in Fig. 1, the valve is set according to the maximum flow of oil, relatively to the size of casing and according to the room to be heated. The collar 8^a is then positioned 70 and retained in such position by the set screw 8^b, thereby permitting a maximum quantity of oil to pass through the supply pipe, never more than a requisite maximum quantity. However, it is obvious that the 80 valve may be gradually closed to decrease the flow of oil.

In Fig. 6 there is disclosed an ordinary form of coal stove in which the improved burner is mounted, resting upon the grate. 85 The burner in this case is slightly modified in detail, but the broad principle and the broad construction are practically the same as in Figs. 1-5. In Fig. 6 since the burner rests upon the grate of the casing 1, and as 90 there are no openings in the bottom of the casing 1 it is necessary to adjust the draft door 4^b which closes the opening 4^a. In other words by regulating the door 4^b it is possible to govern the draft through the 95 grate in order to permit of the proper combustion of the fuel around the burner.

The invention having been set forth, what is claimed as new and useful is:—

1. In a device as set forth, the combination with a casing, an oil cup mounted therein, a gravity feed oil supply pipe for carrying a relatively small but constant flow of oil into the cup, a combined burner support and air supply tube rising upwardly 100 from the bottom of the casing and terminating in a plurality of branch tubes, terminating at diametrically opposite points relatively to the cup for permitting air to mix with the vapor from the fuel in the cup. 110

2. In a device as set forth, a stove casing, an oil or fuel cup therein, a gravity oil supply pipe having a downturned end concentric with and terminating in an oil jet entering the cup, an adjustable sleeve on the downturned end and entering the cup, and means for supporting the cup in the stove casing. 115

3. In a device as set forth, a stove casing, an oil or fuel cup therein, a gravity oil supply pipe having a downturned end concentric with and terminating in an oil jet entering the cup, an adjustable sleeve on the downturned end and entering the cup, means for supporting the cup in the casing, 120 a fire pot under the cup and mounted upon the support, and a baffling member above the cup. 125

4. In a device as set forth, a casing, an oil or fuel cup therein, a gravity oil supply pipe having a downturned end concentric 130

- 4
5. In a device with and terminating in an oil jet entering the cup, an adjustable sleeve on the downturned end and entering the cup, means for supporting the cup in the casing, a fire 65
6 pot under the cup and mounted upon the support, an air chamber surrounding the fire pot, means to supply air therethrough in order to assure and facilitate a proper vaporization of the fuel in the cup, and a heat 70
10 baffling member above the cup.
5. In a device as set forth, a casing, a burner cup therein, a gravity oil feed supply pipe having a downturned end over the cup, a sleeve entering the cup and being 75
15 connected to the downturned end, means for supplying air to the interior of the casing in close proximity to the cup to insure vaporization of the fuel in the cup, means projecting from the bottom of the casing to 80
20 admit an extra supply of air, which circulates about the cup to additionally insure the vaporization of the fuel, a heat baffling member arranged over the cup, and having its lower end of a relatively large diameter
25 and having at its upper end an opening of relatively small diameter, and a combustion chamber above said baffling member.
6. In a device for the purpose indicated, a stove casing, a burner cup therein, means 85
30 for feeding a constant but relatively small flow of oil into the cup, a combined burner support and air supply pipe rising upwardly from the bottom of the stove casing, and supporting said cup and terminating
35 in air tubes to convey air to the space above the cup to assure the vaporization of the fuel, a fire pot below the cup, and a filling of material in the fire pot through which the oil circulates and gradually burns for
40 increasing the heat in the casing.
7. In an apparatus as set forth, a casing, an air chamber in the bottom thereof having communications with the atmosphere under the casing, an air tube rising upwardly from the air chamber, a fire pot adjustable on the air tube, a second air chamber at the upper end of the air tube and having air outlet branch tubes, an oil burner cup mounted on the wall of the second air 105
45 chamber, an oil feed pipe terminating in a jet extending into the cup, and a sleeve adjustable on the jet.
8. In an apparatus for the purpose indicated, a casing, an air chamber supported 110
50 on the bottom of the casing and having communications with the atmosphere under the casing, an air supply tube rising upwardly from the bottom of the air chamber and communicating with the atmosphere under the casing, said air supply tube terminating at its upper end in a second air chamber, a burner proper supported on the wall of the second air chamber, the second air chamber having outlets whereby air from the air 115
55
- supply tube may circulate around the burner proper, and a fire pot carried by the air supply tube and being adjustable thereon relatively to the burner proper and the first air chamber below, to regulate the air relatively to the burner proper. 70
9. In an apparatus for the purpose indicated, a casing, an air chamber at the bottom of the casing and communicating with the atmosphere thereunder, air tubes communicating with the atmosphere under the 75
60 casing and rising upwardly from the bottom of the chamber, an air supply tube terminating in a second air chamber, a burner resting on the second air chamber, a fire pot carried by the air supply tube and being adjustable relatively to the first air chamber below and the burner proper to regulate the air supply surrounding the burner.
10. In an apparatus for the purpose indicated, a casing, an air chamber at the bottom of the casing and communicating with the atmosphere thereunder, an air supply tube terminating in a second air chamber at its upper end, a burner resting on the 90
65 second air chamber, said second air chamber having communication with the space within the casing and around the burner to supply air thereto, and a fire pot carried on the air supply tube and adjustable relatively to the first air chamber at the bottom of the casing, to govern the air supply from the first air chamber through the space between the fire pot and the casing and the space surrounding the burner, in order to regulate the combustion of the fuel. 100
11. In a device as set forth, a casing, an air chamber at the bottom of the casing and communicating with the atmosphere thereunder, an air supply tube terminating in a second air chamber at its upper end, a burner on the second air chamber, said second air chamber having communication with the space within the casing around the burner proper to supply air thereto, a fire 105
70 pot carried on the air supply tube adjustable relatively to the first air chamber at the bottom of the burner, to govern the first air supply from the first air chamber through the space between the fire pot and the wall of said air chamber, in order to regulate the combustion of the fuel, said burner comprising an oil burner cup, a supply pipe terminating in a jet entering the cup, a sleeve adjustable on the jet to 110
75 govern the oil in its flow into the cup, and means surrounding the sleeve for absorbing the fuel from the cup. 115
12. In a device as set forth, a casing, an air supply tube rising upwardly from the bottom thereof and communicating with the atmosphere under the casing and terminating in an air chamber, a burner proper 120
80

supported on said air chamber and comprising an oil receiving burner cup, an oil supply tube terminating in a jet entering the cup, a sleeve mounted on the jet and extending within the cup and having passages at its lower portion to permit the oil to enter the cup, and means surrounding the sleeve and supported on the marginal portion of the cup to absorb the oil from the cup.

10 13. In a device as set forth, a casing, an air tube carried by the bottom of the casing and communicating with the atmosphere thereunder and terminating in an air chamber, a burner proper supported on said air chamber and comprising an oil cup, a relatively small oil feed jet extending into the cup, a sleeve adjustable on the oil feed jet and adjustable relatively to the bottom of the oil cup for controlling the oil in its flow into the cup.

15 14. In a device for the purpose indicated, a casing, an air tube carried by the bottom of the casing and communicating with the atmosphere thereunder and terminating in an air chamber, a burner proper supported on said air chamber and comprising an oil cup, a relatively small oil feed jet extending into the cup, a sleeve adjustable on the jet and adjustable relatively to the bottom of the oil cup for controlling the oil in its flow into the cup, and an asbestos member surrounding the sleeve and supported on the edge of the oil cup to absorb the oil from the cup.

20 15. In a device for the purpose indicated, a casing, an air tube carried by the bottom of the casing and communicating with the atmosphere thereunder, a burner proper at the upper end of the air tube comprising an oil cup, a relatively small oil feed jet extending in the cup, a sleeve adjustable on the jet and adjustable relatively to the bottom of the oil cup for controlling the oil in its flow into the cup, and means for supplying the oil to the jet and including a device for permitting a maximum quantity of oil to feed through the jet.

25 16. In a device for the purpose indicated, a casing, an air chamber supported on the base of the casing, an air tube rising upwardly from said air chamber and terminating at its top in a second air chamber and provided with air branch tubes, a burner supported on the second air chamber, an oil feed for the burner end extending downwardly thereinto, and a fire pot adjustable on the air tube relatively to the two air chambers.

30 17. In a device for the purpose indicated, a common oil stove casing, an air chamber supported on the base thereof, an air tube rising upwardly from the air chamber and communicating with the atmosphere under the air chamber, a fire pot mounted on the

air tube for adjustment into and from the air chamber, means communicatively connecting the air chamber and the atmosphere under the air chamber, a second air chamber at the top of the air tube, a burner supported on the second air chamber, a gravity oil feed pipe having a downturned end terminating in a jet within the burner, a burner cup, and a fibrous absorbent mounted in the cup.

18. In a device for the purpose indicated, a casing, an air tube carried by the bottom of the casing and communicating with the atmosphere thereunder, a burner adjacent the upper end of the air tube comprising an oil cup, an oil feed jet extending into the cup, a feed pipe for said jet, means on said pipe and being of a construction and arrangement for governing the uniformity of the oil supply to the jet, means on the jet for regulating the oil in its flow into the cup, and means for conveying air from the air tube and distributing it at diametrically opposite points relatively to the exterior of the cup.

25 19. In a device for the purpose indicated, a casing, a burner proper in the casing comprising a burner cup, and an oil feed pipe terminating in a downturned oil jet extending into the cup, a sleeve adjustable on the jet and extending into the cup and adjustable relatively to the bottom of the cup for regulating the oil in its flow into the cup, and means for supplying air exteriorly of the cup at a plurality of diametrically opposite points.

30 20. In a device for the purpose indicated, a casing, a burner proper in the casing comprising a burner cup, and an oil feed pipe terminating in a downturned oil jet extending into the cup, a sleeve adjustable on the jet and extending into the cup and adjustable relatively to the bottom of the cup for regulating the oil in its flow into the cup, means for supplying air exteriorly of the cup at a plurality of diametrically opposite points, and a fibrous absorbent on the cup movable on the sleeve.

35 21. In a device for the purpose indicated, a casing, a burner proper comprising a gradual feed oil jet, an oil cup into which the jet extends, means communicating with the atmosphere under the casing for delivering air exteriorly of the cup at diametrically opposite points thereof, means for carrying the oil to the cup and having means to regulate the feed to provide different but uniform supplies of oil to the cup.

40 22. In an apparatus for the purpose indicated, a casing, an air chamber on the bottom of the casing and being in communication with the atmosphere under the bottom of the casing, an air tube rising upwardly from the bottom of the air chamber

and being in communication with the atmosphere under the casing, a fire pot adjustable on said air tube, a second air chamber on the upper end of the air tube, a burner supported thereon, means for supplying oil to the burner, said second air chamber having a plurality of branches for delivering air to the burner at a plurality of diametrically opposite points, and metallic wool contained in the fire pot, in order to facilitate the burning of the oil.

In testimony whereof I hereunto affix my signature.

HENRY B. HEMPHILL.
